ULTRASHORT WAVE RESONANCE SYSTEM

Hans Erich Hollmann, Berlin, Germany, assignor to Telefunken Gesellschaft für Drahtlose Telegraphie m. b. H., Berlin, Germany, a corporation of Germany

Application September 28, 1935, Serial No. 42,586
In Germany September 15, 1934

7 Claims. (Cl. 250—36)

This invention relates to electron discharge device electrical oscillators, and more particularly to thermionic tube oscillator circuits suitable for use in ultra short wave systems.

5 In the production of oscillations of extremely high frequency such as of the order of from 100 to 1000 megacycles by means of a back coupled tube transmitter, it is known to be very difficult, in matching the oscillatory circuit excited by the 10 tube with the inner tube resistance (internal impedance of the tube), to maintain a sufficient operating voltage, and to provide an optimum of utilization of the tube, in view of the fact that the apparent resistance of the load circuit becomes steadily lower with increasing frequency due to the predominantly capacitive action of said load circuit. However, a much better matching and utilization of energy can be obtained by 15 means of an oscillatory system in which the inductance and the capacity are uniformly distributed.

The details of my invention will be better understood upon reading the following description in view of the accompanying drawing in which

25 Figure 1 shows diagrammatically one embodiment of an oscillatory system having symmetrical impedances in circuit with an electron discharge tube;

Fig. 2 shows a development of the underlying scheme, where four electron discharge tubes are symmetrically connected in circuit with a spherically formed load; and

Fig. 3 shows certain structural details of an embodiment of the invention in which two electron discharge tubes may be employed.

35 Referring to Fig. 1, the resonance system which in fact represents the load of the tube, comprises two hemispherical cups, or bowls S_1 and S_2 mounted on a common axis in the form of a rod or tube 40 A, A and representing the inductance, while the capacity is mainly formed by two equatorial flanges F_1 and F_2 . The electrical condition of oscillation of such a hollow body corresponds to its mode of mechanical oscillation. In other 45 words, the electrical oscillation is such that there will be an oscillation node in the center of the axis, whereas the potential loops (voltage anti-nodes) appear at the flanges, at which places, therefore, the grid and anode of the exciting oscillatory tube are connected in the manner shown 50 in Fig. 1.

This known arrangement, however, has the defect that the unilateral connections of the tubes disturb the uniform distribution of the capacity 55 of the oscillatory circuit on the periphery of the

flanges and cause a detrimental effect by making it difficult to match the impedances of the oscillatory system. In order to avoid this defect, the present invention provides a more uniform excitation of the resonance system by replacing the single tube by several tubes distributed over the periphery of the resonance system. In view of this distribution of the individual tube capacities over the periphery of the spherical oscillatory circuit system and to the multiple excitation thereof from different points, there is obtained the further considerable practical advantage that upper harmonics which tend to occur with great prominence in an unsymmetrical construction are, to a large extent, suppressed. If, on the other hand, 10 it is desirable for special purposes such as for frequency multiplication, to provide a possibly large number of upper harmonics, the tubes may be irregularly distributed around the periphery so as to obtain oscillation loops (anti-nodes) at 15 the centers of excitation established by the points of connection. While at fundamental oscillation all tubes operate in synchronism, they may in the latter case also operate in push-pull, particularly if an oscillation node lies in the circuit 20 between two tubes.

In some cases where the frequency to be generated is not too high and the power output required is not too great, i. e., the tubes employed are small enough, the tubes can be entirely accommodated within the hollow structure constituting the oscillatory system. A symmetric and radial arrangement of the tubes will probably be best suited for such a case because such an arrangement permits the cathodes to be directly 30 connected to the center of the axis where an oscillation node exists, while the grid and plate leads can be directly connected to the two flanges. In this manner connections carrying high frequency do not appear at all outside the tubes, a 35 condition which is of particular advantage in connection with the proper phase adjustment of ultra-short wave feedback energy.

If the tubes are too large to be housed entirely within the oscillating hollow body, the glass of 45 the tubes may protrude from openings provided in the resonance body without thereby causing an appreciable detrimental effect upon the electrical conditions of ultra-short wave transmitters. This idea of the invention is illustrated in the arrangement according to Fig. 3. The cathodes of the two tubes R_1 and R_2 shown in cross section are directly connected to the axial tube A disposed in the axis across which the heating current is likewise introduced, while the remaining heating 50

lines are brought out through the interior of the axial tube. The direct grid and plate potentials are supplied across the two spherical cups; hence they must be insulated from the axis as regards 5 direct current, by means of cylindrical condensers C_1 and C_2 . It is advisable to block all feed lines against high-frequency by means of chokes D . The high frequency power generated may be taken off from the spherical oscillatory circuit 10 structure either by means of a coupling loop, or across a supply line connected to two points in the axis and brought out through suitable apertures in the spherical cups.

I claim:

- 15 1. An ultra-short wave oscillator comprising an oscillatory circuit in the form of a pair of hemispherical conductive members substantially conforming to a spherical surface and having substantially distributed inductance and capacitance, 20 a plurality of space discharge tubes symmetrically disposed with respect to said members, and means including connections between the input and output electrodes of said tubes and different points on said conductive members for balancing the 25 impedances of said oscillator internally and externally of said tubes.
- 15 2. An ultra-short wave oscillator comprising an oscillatory circuit in the form of a pair of hemispherical conductive members substantially conforming to a spherical surface and having substantially distributed inductance and capacitance, 30 a plurality of space discharge tubes symmetrically disposed with respect to said members and disposed in recesses formed in said hemispherical 35 members, and means including connections between the input and output electrodes of said tubes and different points on said conductive members for balancing the impedances of said oscillator internally and externally of said tubes.
- 40 3. An oscillator in accordance with claim 2 and having coaxial conductors for feeding the cathodes of said tubes with heating current, said coaxial conductors being disposed within the hemispherical surfaces of said conductive members.
- 45 4. A very high frequency electron discharge device oscillator having an electrically resonant oscillatory system constituted by a hollow conducting structure which is symmetrical about its axis,

characterized in that there are a plurality of oscillating electron discharge devices connected to said structure, the points of connection of said devices to said structure being spaced round the periphery thereof to provide additional capacities distributed around said structure at said points of connection. 5

5. A very high frequency thermionic valve oscillator having an electrically resonant oscillatory system constituted by a hollow structure with 10 distributed inductance and capacity and consisting of an axially arranged conductor diametrically and symmetrically disposed with respect to a pair of substantially hemispherical conductive caps arranged one at each end of said conductor, 15 characterized in that there are a plurality of oscillating electron discharge devices with their control grids connected to one cap at or near the rim thereof and their anodes connected to the other cap at or near the rim thereof, the points 20 of connection of the different devices to said caps being spaced round the cap rims, the point of connection of any control grid to one rim being substantially opposite the point of connection of the anode of the same device to the other rim. 25

6. A short wave system comprising, in combination, a plurality of electron discharge device oscillators each having an output circuit, and an electrically resonant oscillatory circuit effectively coupled in parallel to the outputs of said oscillators, said oscillatory circuit comprising a hollow structure symmetrically disposed with respect and connected to an axially arranged conductor, said electron discharge devices being substantially evenly distributed around said hollow structure. 30

7. A very high frequency electron discharge device oscillator having an electrically resonant oscillatory system constituted by a hollow conducting structure which is symmetrical about its axis, characterized in that there are a plurality of 40 oscillating electron discharge devices connected to said structure, the points of connection of said devices to said structure being irregularly spaced around the periphery thereof, whereby the upper harmonics of the fundamental frequency are 45 produced.
